GUIDING AND CUSHIONING MEANS FOR
SLIDABLE WINDOW PANESJames S. Reid, Shaker Heights, Ohio, assignor, by
mesne assignments, to The Standard Products
Company, Cleveland, Ohio, a corporation of
Ohio

Application April 20, 1933, Serial No. 667,061

11 Claims. (Cl. 296—44.5)

This invention relates to improvements in guiding and cushioning means for slidable window panes and more particularly, to such means especially adapted for use with specially shaped window openings or window panes therefor, such as the front windows of many present day automobiles. The windshields of such automobiles are rearwardly inclined and by specially shaping the openings and the upper front corner portions of the panes of such windows, the front edges thereof may be given a rearward inclination corresponding to that of said windshields, with consequent improvement in the appearance of said windows.

To properly support and guide a vertical edge portion of such a window pane, a piece of standard form window channel, having side walls of uniform and standard depth, may be satisfactory without modification thereof or additions thereto, but to properly support and guide an inclined edge portion of such a window pane, special window guiding means may be desirable or necessary, all as will hereinafter more fully appear.

The general object, therefore, of the present invention is the provision, for supporting and guiding an inclined edge portion of such a window pane, of such special guiding means and more specifically, an improved form thereof which provides flat cushioning and guiding strip members which are presented and applied flatwise to the faces or side surfaces of the window pane, so that such pane may extend beyond both longitudinal edges of each such strip member, and which strip members may be simply and inexpensively formed in any suitable manner, such as by providing a portion or section of a standard form window channel with suitable supplemental side walls of increased depth and so constructed and arranged as to enable the inclined edge portion of such a window pane to be properly supported and guided during its movement.

A more specific object of the present invention is the provision of such special window guiding means in which the supplemental side walls thereof are provided, in a simple and economical manner, with window-engaging cushioning means along their inner surfaces and with such cushioning effects along their outer surfaces as to effectively prevent rattling of said supplemental side walls in the window frame groove in which they are adapted to be arranged in use thereof.

With the foregoing and other objects in view which will appear as the description of the invention proceeds, the invention resides in the combi-

nation and arrangement of parts and in the details of construction hereinafter described and claimed, it being understood that changes in the invention as here disclosed can be made within the scope of what is claimed without departing from the spirit of the invention.

The present invention will be readily understood from the following description of two embodiments thereof, reference being had to the accompanying drawings in which

Fig. 1 is a side elevation of a portion of a body of a present day automobile, said body having installed in the door thereof special window guiding means embodying the present invention; Fig. 2 is a side elevation of a portion thereof, part of one of the side walls being broken away to illustrate interior construction; Figs. 3 and 4 are respectively cross sectional views thereof on the lines 3—3 and 4—4, Fig. 2; Fig. 5 is a view similar to Fig. 1 and showing installed in the door special window guiding means also embodying the present invention; Fig. 6 is a side elevation of a portion of the guiding means shown in Fig. 5; Fig. 7 is a perspective view of the sheet metal core and reinforcing wires of the standard form window channel shown in Fig. 4, other parts of such channel being omitted in Fig. 7; and Fig. 8 is a perspective view, with successive layers of the cushioning material partly broken away, of one of the flat guiding and cushioning strip members shown in Fig. 3.

The portion 1 of the automobile body shown in Fig. 1 includes a suitable door 2 provided in its upper portion with a suitable window opening 3 adapted to be opened and closed by a suitable sashless glass window pane 5 mounted in said door for vertical sliding movement. The windshield (not shown) of said automobile and the front edge of the window opening 3 thereof are rearwardly inclined and in order to give the front edge portion 7 of the top part of the window pane 5 a corresponding rearward inclination, the upper front corner portion of said window pane is specially shaped, so that the top part of said window pane, from the point marked X, Fig. 1, to the top edge 8 thereof, is of gradually decreasing width.

To properly support and guide the rear edge portion 10 of said window pane, under conditions such as illustrated in Fig. 1, a piece 25 of standard form window runway or channel, having side walls of uniform and standard depth, may be satisfactory without modification thereof or additions thereto, such as the runway or channel disclosed in my prior Patent No. 1,918,666, granted July 55

18, 1933, to which patent reference may be had, if desired.

So far as description is here necessary, said standard form channel includes a generally channel shaped resilient sheet metal core or body member having a base 15 and a pair of generally parallel side walls 16 terminating at their outer longitudinal edge portions in longitudinally disposed beads 17 in which are arranged longitudinally disposed re-enforcing wires 18. To give said channel sufficient flexibility, etc., the base and side walls thereof are provided with transversely disposed slots 19, extending from one side wall, at points adjacent the bead 17 thereof, through the base 15, to points adjacent the bead 17 of the other side wall, as clearly shown in Fig. 7. Preferably and as here shown, said base and side walls are enclosed in a suitable covering 20, of vulcanized rubber or the like, and in order to protect said covering and to further cushion the window pane 5 which this runway or channel is adapted to receive, a suitable cushioning sheet 21 of felt or the like is longitudinally arranged within said channel, said sheet lying alongside the rubber covered inner surfaces of the base and side walls thereof. As here shown, said cushioning sheet 21 is of sufficient width to enable its side edge portions to be turned or folded laterally outward around the side walls 16 of said runway or channel core member, and to lie alongside the rubber covered outer surfaces of said side walls, terminating adjacent the rubber covered base 15 of said channel core member.

Due to the inclination of the front edge portion 7 of the top part of said window pane 5, special window guiding means may be preferable to properly support and guide the front edge portions of the top and bottom parts of said window pane. Such special window guiding means may be simply and economically made by providing a portion or section of a standard form window channel with suitable supplemental side walls of greater depth than the side walls of said standard form channel.

In the embodiment of the invention illustrated in Figs. 2 and 3, a piece 30 of standard form window channel has an intermediate portion or section thereof provided with supplemental side walls 35, here shown as integral parts of a sheet metal member of generally channel shape so that it also includes a suitable base 36. As best shown in Figs. 3 and 4, said sheet metal member is just wide enough to receive the base of the standard form channel, and as best shown in Figs. 1 and 2, the side walls of said sheet metal member are of varying depth, having a minimum depth substantially the same as that of said standard form channel side walls and a maximum depth substantially three times that of said standard form channel side walls. As shown in Fig. 1, this special composite channel structure of Fig. 2 is suitably arranged in the door 2 along the front edge portion thereof, an intermediate portion or section of said structure, with its sheet metal member secured thereto in the manner hereinafter described, being arranged just below the window opening 3 and the upper portion or section of said structure lying along the front edge portion of said window opening and having a rearward inclination corresponding thereto.

The securing of the sheet metal member to the standard form channel is effected by disconnecting the side walls of said channel from the base thereof, and then associating said disconnected base with the base 36 of said sheet metal

member and also associating said disconnected side walls with the side walls 35 of said sheet metal member. For this purpose, the side walls 35 are provided along the base thereof with suitable clamping tongues 40 struck from said side walls and bent laterally inward over said disconnected standard form channel base, thereby clamping said disconnected base against the base of said sheet metal member. Likewise, the side walls 35 are provided in their outer longitudinal edge portions with suitable tongues 42 struck from said side walls and bent laterally inward over the inner longitudinal edge portions of said disconnected standard form channel side walls and over those faces thereof which are toward the window pane 5, thereby clamping said disconnected standard form channel side walls against the inner surfaces of the outer longitudinal edge portions of the side walls 35. The side walls of the composite structure thus formed are therefore provided, in a simple and economical manner, along their outer longitudinal edge portions with two opposed flat guiding and cushioning strip members for the slidable window pane 5, each such strip member being formed, in the particular embodiments of the invention here shown, from a side wall of a standard form channel, the arrangement being such that each of said strip members has the entire area of one face thereof presented flatwise to one face or side surface of the window pane 5 which therefore may extend beyond both longitudinal edges of each such strip member, the latter offering ample cushioning support to the window pane during its movement.

The formation of the clamping tongues 40 and 42 respectively provides in the side walls 35 longitudinally disposed apertures 44 and 45, the apertures 45 being partially covered from the inside by the aforesaid flat window pane guiding and cushioning strip members. As best shown in Fig. 3, portions 48 of the cushioning material of said flat strip members, project through said apertures 45 and thus provide along the outer surfaces of the supporting side walls 35 cushioning effects which quite satisfactorily prevent said supporting walls from rattling, etc., in the door frame groove in which it is placed in use thereof, all as will be readily understood.

If desired, the rear edge portion of the window opening 3 may be specially shaped, such as by giving it a forward inclination corresponding to the rearward inclination of the front edge portion of said window opening. In Fig. 5, the rear edge portion of the window opening 3a of door 2a has such a forward inclination, which is taken care of by providing the upper portion or section of the standard form window channel 25a with a sheet metal member of the same type as the one with which an intermediate portion or section of the front standard form channel 30 of Fig. 1 is provided. As clearly shown in Figs. 5 and 6, the side walls 55 of the sheet metal member of this standard form channel 25a are of gradually increasing width, from bottom to top, so that the window opening 3a of Fig. 5 is not only of symmetrical appearance but also, the vertically movable rear edge portion 10a of the window pane 5a is more firmly, and to a greater extent, supported in the composite upper portion or section of the runway or channel 25a, the two flat guiding and cushioning strip members of the upper portion or section of such channel 25a being bent edgewise or in their own planes to conform to the inclination of the rear edge por-

tion of the window opening 3a, all as will be readily understood.

Further features of the present invention will be apparent to those skilled in the art to which the invention relates.

What I claim is:

1. A window runway or channel, comprising a generally channel-shaped member having a base and a pair of window-pane receiving side walls separated therefrom and provided with window-pane engaging cushioning means, and a pair of supplemental side walls for said member associated with the base thereof and provided with longitudinally spaced apertures, said structure side walls being arranged along the inner surfaces of said supplemental side walls, adjacent the apertures thereof, and the window-engaging cushioning means of said member side walls having portions thereof projecting laterally outwardly through the apertures in said supplemental side walls, whereby cushioning effects are provided by said cushioning means along the outer surfaces of said supplemental side walls. 10
2. A window runway or channel, comprising a generally channel-shaped member having a base and a pair of window-pane-engaging side walls separated therefrom and of uniform depth, and a pair of supplemental side walls of varying depth for a portion or section of said member and associated with the base thereof, the member side walls of said portion or section being secured to said supplemental side walls, adjacent the outer edge portions thereof, by means of tongues with which said supplemental side walls are provided. 15
3. A window runway or channel, comprising a generally channel-shaped main member having a base and a pair of window-pane engaging side walls separated therefrom, and a supplemental member for said main member and having a base and a pair of side walls of greater depth than the depth of said main structure member side walls, said main member side walls and said main member base being respectively secured in assembly with the side walls and the base of said supplemental member by means of tongues with which said supplemental member is provided. 20
4. A window runway or channel, comprising a generally channel-shaped main member having a base and a pair of window-pane engaging side walls separated therefrom, and a supplemental member for said main member and having a base and a pair of side walls of greater depth than the depth of said main member side walls, said main member side walls and said main member base being respectively secured in assembly with the side walls and the base of said supplemental member by means of tongues with which the side walls of said supplemental member are provided. 25
5. A window runway or channel, comprising a generally channel-shaped window-pane-receiving member having a base and a pair of window-pane-engaging side walls separated therefrom, said member side walls being provided at their outer longitudinal edges with longitudinally disposed beads, and a pair of supplemental side walls for said member associated with the base thereof, said member side walls being secured to said supplemental side walls in such manner that the longitudinally disposed beads of said member side walls lie outwardly beyond the outer longitudinal edges of said supplemental side walls. 30
6. In combination, a generally flat guiding and cushioning strip member for engagement with one face of a slidable window pane, a supporting wall for such strip member, the width of said wall being greater than the width of said strip member, the general plane of said wall and the general plane of said strip member being substantially parallel with that of said window pane, and clamping means carried by said wall and engaging said strip member along one of its longitudinal edge portions for securing said strip member to said wall, said clamping means engaging that face of said strip member which is toward said 35 window pane.
7. In combination, a generally flat guiding and cushioning strip member for engagement with one face of a slidable window pane, a supporting wall for such strip member, the width of said wall being greater than the width of said strip member, the general plane of said wall and the general plane of said strip member being substantially parallel with that of said window pane, and clamping tongues integral with said wall and engaging said strip member along one of its longitudinal edge portions for securing said strip member to said wall, said clamping tongues engaging that face of said strip member which is toward 40 said window pane.
8. In combination, a generally flat guiding and cushioning strip member for engagement with one face of a slidable window pane, a supporting wall for such strip member, the width of said wall being greater than the width of said strip member, the general plane of said wall and the general plane of said strip member being substantially parallel with that of said window pane, and a plurality of longitudinally spaced clamps carried by said wall and engaging said strip member along one of its longitudinal edge portions for securing said strip member to said wall, said clamps engaging that face of said strip member which is toward 45 said window pane.
9. A generally flat guiding and cushioning strip member for slidable window panes, said strip member comprising a generally flat transversely slotted sheet metal body portion, said slots extending through one of the longitudinal edges of said body portion, and yieldable cushioning means for said body portion, said strip member being adapted for application to one face of a slidable window pane with the entire area of one face of the strip member presented flatwise to such window pane for guiding and cushioning the same, 50 whereby the window pane may extend beyond both of the longitudinal edges of the strip member.
10. A generally flat guiding and cushioning strip member for slidable window panes, said strip member comprising a generally flat sheet metal body portion having a longitudinally disposed bead along one of its longitudinal edges and transversely disposed slots extending from points adjacent said bead through the other edge of said body portion, and yieldable cushioning means for said body portion, said strip member being adapted for application to one face of a slidable window pane with the entire area of one face of the strip member presented flatwise to such window pane for guiding and cushioning the same, whereby the window pane may extend beyond both of the longitudinal edges of the strip member. 55
11. A generally flat guiding and cushioning strip member for slidable window panes, said strip member comprising a generally flat sheet metal body portion having a longitudinally disposed bead along one of its longitudinal edges and transversely disposed slots extending from points ad- 60

5 jacent said bead through the other edge of said body portion a longitudinally disposed reinforcing wire arranged in said bead, and yieldable cushioning means for said body portion, said strip member being adapted for application to one face of a slidable window pane with the entire

area of one face of the strip member presented flatwise to such window pane for guiding and cushioning the same, whereby the window pane may extend beyond both of the longitudinal edges of the strip member.
